UNITED STATES PATENT OFFICE.

JOSEPH NADER, OF WAUKESHA, WISCONSIN.

BOTTLE-FILLING MACHINE.

963,801.

Specification of Letters Patent. Patented July 12, 1910.

Application filed April 8, 1909. Serial No. 488,660.

To all whom it may concern:

Be it known that I, JOSEPH NADER, a citizen of the United States, residing at Waukesha, in the county of Waukesha and State 5 of Wisconsin, have invented certain new and useful Improvements in Bottle-Filling Machines; and I do declare the following to be a full, clear, and exact description of the invention, such as will enable others skilled 0 in the art to which it appertains to make and use the same.

My invention relates to bottle filling machines which are used to insert syrup of all kinds, which are used in the manufacture 5 of soft drinks, such as ginger ale, root beer, etc.

The object of the invention is to provide and place a machine of this character within the reach of all by constructing a machine in such a manner that its parts are few and inexpensive to make, and by providing a machine which may be readily and efficiently operated.

A further object of the invention is the provision of means whereby the liquid is measured in desired quantities and automatically fed to the bottles as they rise to receive the discharge spouts.

A further object of the invention is the provision of means to guide the bottles to the discharge spouts, and to automatically release and to automatically open the discharge spouts to the bottles after performing the guiding function.

With these and other objects in view, the invention consists of certain novel features of construction, combination and arrangement of parts, as will be more fully described and particularly pointed out in the 0 appended claims.

In the accompanying drawings, Figure 1 is a front elevation, Fig. 2 is a side elevation, Fig. 3 is an enlarged longitudinal section of the upper part of the machine, Fig. 4 is a transverse vertical section on the line 4-4 of Fig. 1, Fig. 5 is a section on the line 5-5 of Fig. 3, Fig. 6 is a transverse section on the line 6-6 of Fig. 1, Fig. 7 is a vertical transverse section on the line 7-7 of Fig. 3, Fig. 8 is a horizontal section on the line 8-8 of Fig. 1, Fig. 9 is a transverse section on the line 9-9 of Fig. 8, and Fig. 10 is a transverse section on the line 10-10 of Fig. 6. Fig. 11 is a detail vertical section of one 5 of the plungers on an enlarged scale.

Referring more especially to the drawings,

1 and 2 represent base pieces from which the standards 3 and 4 project. These bases are braced in any suitable manner (not shown), and have journaled in their upper 60 portions the operating shaft 6, to which is pivotally attached the hand lever 7 and the cranks 8. As these parts relate to the operation of the device they will be described more minutely hereinafter. 65

Mounted rigidly upon the top of the standards is a tank 9, which is cast as a whole with outwardly projecting arms 10, which are provided with standard receiving sockets 11, and suitable set screw openings 70 12, in which set screws 13, are mounted to engage the standard and hold the device rigidly in position. This tank is provided with a plurality of inwardly raised bosses 13' and depending bosses 14, and through 75 both of them is formed the attaching neck apertures 15. The tank is also provided with suitable apertures 16 and 17, to which the inlet and outlet pipes 18 and 19 are attached. Suitably mounted within the tank 80 are a plurality of piston cylinders 20, each having a depending attaching neck 21, which passes through the openings 15 and is provided with a locking nut 22, to clamp the cylinder to the casing. The outer end 85 of this neck 21 is provided with a nut 23, which holds suitable packing 24 around the valve tube 25, which slides therein. This valve tube extends up in the casing some little distance and normally rests immediately below an inlet port 26, formed therein, which permits when in register with a similar opening 27 in the valve tube, the fluid to pass into the measuring cylinder 20. Below the aperture 27 and on the opposite side of 90 the valve tube 25 I provide another aperture 28, for the outlet of the fluid from the casing 20 to the valve tube. The lower end of this tube is provided with an annular collar 29, which is adapted to rest upon the top 95 of the valve tube supporting plate 30, and be clamped thereto by a locking nut 31, which engages underneath the plate upon the threaded end of the tube 25. In order to prevent turning of each tube I preferably 100 aperture the collar 29, as at 32, and pass a screw 33, therethrough into the plate. The interior of the end of the tube opposite the jam nut 31 is threaded to receive a discharge tube 34, which is of somewhat 110 smaller diameter and is provided at its lower end with a guiding head 35, seated in

the end and beveled upon its upper side as at 36, to direct the fluid to the outlet opening 37, formed upon the side and covered by the collar 38, carried upon the upper end 5 of the guiding funnel 39. These funnels are formed so as to guide the discharge tubes 34 into the bottle neck and are apertured at 40, to permit the escape of air.

The valve plate 30 is constructed in a 10 similar manner to the tank 9, in that it has a pair of arms 41, projecting outwardly therefrom and provided with depending bearing members 42, which slidably receive the standards 3 and 4. In line with these 15 standard bearing members I provide a pair of apertures 43, one in each arm so as to receive the operating rods 44. These rods are rigidly held within the valve plate by clamping nuts 45 and 46. The operation of 20 the rods 44 will be described hereinafter.

Each piston cylinder 20 is provided with a piston 47, whose rod 48, is hollow, to permit air to escape and extends upwardly through an aperture 49, formed in a supporting plate 50. A suitable float valve 25 might be arranged in the tubes 48 to prevent liquid from entering the same, but this has been found unnecessary as the tubes have an extremely small aperture and the amount of 30 liquid therein is almost negligible. This supporting plate is carried upon a depending rod 51, which is passed through a bushed opening 52, formed in the yoke member 53, which extends over the top of the tank. 35 The upper end of the rod 51 is threaded to receive the hand wheel 54, so that the plate 50 may be adjusted up and down in the yoke member as is desired, and thereby operate the pistons to determine the quantity 40 of the charge admitted to the cylinders.

Slidably mounted upon the standards 3 and 4 below the valve plate 30 is the bottle supporting table 55, constructed in a similar manner to the tank and to the valve 45 plate, in that it has a pair of arms 56, extending outwardly from the body of the table and provided with bushed standard receiving sockets or apertures 57, through which the standards pass. Outside of these 50 sockets the arms are provided with pin receiving lugs 58, which receive the pins 59, of the connecting links 60. These links 60 are connected to the crank arm 8 by a pivotal pin 61, and at its opposite end to the pin 59. In order to make the device adjustable so as to raise the bottle supporting plate 55 different distances I provide a plurality of apertures 62, in the link so that the adjustment may be attached. Alining with the 60 apertures 43 in the plate 30 are a pair of bushed openings 63, formed in the plate 55 so as to permit the rods 44 to work up and down therein for a predetermined distance. This movement of the plate allows the bottles 65 to become centered in the funnels 39

and to push them off their seats so that the port 37 is opened before the valve plate is moved.

Secured upon the rods 44 above and below the table 55 are a pair of adjustable 70 collars 64 and 65, the former of which limits the downward movement of the table 55, and the latter of which being engaged by the table raises the rods 44 and consequently the plate 30, and all of the valve tubes 25 75 so that the inlet port 26 is closed from the tank into the piston cylinders, and the outlet port 28 is opened to the piston chambers. The liquid flows out through the opening into the bottles. When the valve tubes are 80 again lowered and the ports 26 and 27 are co-incident the liquid again flows into the cylinders until they are filled up to the pistons, the air going out through the aperture therein shown in Fig. 11. The valve tubes 85 are forced down to their seats by reason of the table platform engaging one of the collars which surrounds the operating rod 44.

The bottle plate is provided with a plurality of apertures 66, which are adapted to 90 reduce the weight, and the edge of the table is slightly upturned so as to prevent the possible slipping of the bottle crate (not shown).

Secured to the shaft 6 intermediate the 95 standard is a lever 68, having a plurality of apertures 69, in one of which is secured the hook of the inertia weight 70, which assists in overcoming the inertia of the bottle table and the bottles thereon. 10

From the foregoing description, taken in connection with the accompanying drawings, the construction and operation of the invention will be readily understood without requiring a more extended explanation. 10

Various changes in the form, proportion and the minor details of construction may be resorted to without departing from the principle or sacrificing any of the advantages of this invention as defined in the appended claims. 11

Having thus described my invention, what I claim and desire to secure by Letters Patent is:—

1. In a bottle filling machine, the combination with a supply tank, of a plurality of valve feeding tubes depending therefrom and connected therewith, means connecting all of said valve tubes, means for supporting a plurality of bottles, means for elevating said bottle supporting means, and means controlled in the movement thereof for raising said valve tube connecting means and putting the valves in feeding position. 11

2. In a bottle filling machine, the combination with a supply tank, of a plurality of valve tubes depending therefrom and connected therewith, a valve plate connecting all of said valve tubes, means for supporting a plurality of bottles, means for elevating said 12

bottle supporting means, and rods carried by said valve connecting plate adapted to be operated after a predetermined elevation of the bottle supporting means whereby the valves 5 are placed in feeding position.

3. In a bottle filling machine, the combination with a supply tank, of a plurality of valve feeding tubes depending therefrom and connected therewith, a plate connecting 10 all of said valve tubes, a pair of rods rigidly depending therefrom, a bottle supporting table, collars on said rods for causing the downward movement of said plate, means for raising said table, and auxiliary collars 15 adapted to be engaged by said table to raise the valve supporting plate and put the valves in feeding position.

4. In a bottle filling machine, the combination with a supply tank, of a plurality of 20 feeding tubes connected thereto, apertured discharge extensions connected to said tubes, bottle guiding means carried by the discharge extensions for closing the apertures in the extension, and means for elevating the 25 bottles to be filled thereby operating the guiding means to uncover the feeding aperture in the discharge extensions.

5. In a bottle filling machine, the combination with a supply tank, of a plurality of 30 reciprocally mounted valve tubes depending therefrom, apertured discharge extensions rigidly connected to said tubes, bottle guiding funnels loosely mounted upon the ends of the discharge extensions for closing the 35 apertures in the extensions, and means to elevate the bottles to be filled and through the bottles operate said funnels to raise them from the feeding apertures in the discharge extensions.

6. In a bottle filling machine, the combination with a supply tank, of a plurality of measuring cylinders mounted therein, pistons in said cylinders, means for adjusting said pistons to determine the charge admitted to the cylinders, an apertured bottle 40 feeding tube adapted to reciprocate within each of said cylinders, means to operate said feeding tube to close the inlet port to said cylinders from the supply tank and to open the aperture therein for discharging the 45 liquid, and means to close the discharge end of the tube until engaged by the bottle to be filled.

7. In a bottle filling machine, the combination with a supply tank, of a plurality of 50 measuring cylinders mounted therein, each cylinder being provided with an inlet port, pistons in said cylinders, a yoke carried by the top of said measuring tank, a hand operated device carried by said yoke, a plate 55 attached to all of the pistons, means connected to the plate and to the hand operated device for raising and lowering said pistons, and apertured bottle feeding tube for each of said cylinders, means to raise said tube 60 within the cylinders whereby the inlet port 65 may be closed and its feeding aperture opened, and means to close the discharge end of said tubes until engaged by the bottles to be filled.

In testimony whereof I have hereunto set my hand in presence of two subscribing witnesses.

JOSEPH NADER.
